FOLDING POCKET FAN

Filed May 8, 1943

FIG. 7.

FIG. 5.

INVENTOR.

Louis Bernstein

BY

John H. Polashik

ATTORNEY

UNITED STATES PATENT OFFICE

2,371,792

FOLDING POCKET FAN

Louis Bernstein, Brooklyn, N. Y.

Application May 8, 1943, Serial No. 486,130

5 Claims. (Cl. 230—268)

This invention relates to new and useful improvements in a folding pocket fan.

More specifically, the invention proposes the construction of a folding pocket fan characterized by a flat fan blade to which a handle is pivotally attached in a manner to permit the fan blade and handle to be folded into a superimposed position, one on the other, to reduce the length of the fan, permitting it to be carried in a purse or pocketbook or in a pocket of one's clothing.

Still further it is proposed to characterize the handle by a flat strip of sheet material which is bent at its center forming side arms which are slightly longer than the length of the fan blade and having the ends of its side arms engaging over opposite faces of an edge portion of the fan blade with a fold engaged through the overlapping portions of the arms and fan blade in a manner to permit the fan blade to be extended from the handle or be pivoted to an inoperative position between the side arms of the handle.

Still another object of the invention proposes the provision of a pair of strips mounted on said pintle adjacent the inner faces of said side arms and having top lugs attached to the side arms and provided with a fastening means arranged in a manner to releasably grip the edge portion of the blade to maintain the blade and handle in a releasable operative position.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a folding pocket fan constructed in accordance with this invention, and in its collapsed condition.

Fig. 2 is a view similar to Fig. 1 but illustrating the fan in its operative extended position.

Fig. 3 is an enlarged sectional view taken on the line 3—3 of Fig. 2.

Fig. 4 is an elevational view of a folding pocket fan constructed in accordance with a modification of this invention.

Fig. 5 is an enlarged partial sectional view taken substantially on the line 5—5 of Fig. 4.

Fig. 6 is a view similar to Fig. 4 but illustrating a further modification of the invention.

Fig. 7 is an enlarged partial vertical sectional view taken on the line 7—7 of Fig. 6.

The folding pocket fan, according to this in-

vention, includes a flat fan blade 10. This fan blade is formed of heavy cardboard and is disc-shaped. The opposite faces of the fan blade 10 are adapted to be imprinted with advertising material 11.

A handle 12 is provided for the fan blade 10. This handle is constructed of a flat strip of sheet material, such as cardboard or the like, and is bent at its center producing side arms 14.

The strip should be of such length that when it is bent at its center the side arms 14 will be of a length slightly greater than the height of the fan blade 10. The arms 14 have their free ends extended along opposite sides of an edge portion of the blade 10 as clearly shown in Fig. 3.

A pintle 15 is engaged through the ends of the arms 14 and the adjacent edge portion of the fan blade 10. The pintle 15 is in the form of a rivet.

20 The operation of the device is as follows:

When the fan is being used the fan blade 10 is pivoted into an operative position with the handle 12, as shown in Fig. 2. However, it is possible to pivot the fan blade 10 into an inoperative position between the adjacent faces of the side arms 14 of the handle 12, as clearly shown in Fig. 1. This materially reduces the operative length of the fan permitting it to be carried in a purse or pocketbook, or in a pocket of one's clothing.

25 In the form of the invention shown in Figs. 4 and 5 the construction of the folding fan is similar to that previously described, except that the fan blade 10' is hexagonally shaped and a slightly different pintle 15' is employed for pivotally connecting together the hexagonal fan blade 10' and the side arms 14 of the handle 12. In this form of the invention the pintle 15' is in the nature of a paper type cotter pin which is extended through aligned openings formed in the fan blade 10' and the arms 14 of the handle 12. The free ends of the arms of the paper type cotter pin are then bent over to extend along the outer face of the adjacent side arm 14 of the handle 12. A disc of paper 16 is pasted into position over the bent ends of the side arms of the cotter pin 15' for covering these free ends to maintain the pin against rotation and to prevent one's fingers from coming in contact therewith and being cut thereby.

30 In other respects this form of the invention is identical to the previous form and like parts are identified by like reference numerals.

35 In the form of the invention shown in Figs. 6 and 7 the construction of the folding pocket fan

is similar to that shown in Figs. 1 to 3, except for the provision of means for locking the blade 10 in its operative position with relation to the handle 12. In this form of the invention washers 17 are mounted upon the pintle 15 in face contact with the sides of the blade 10. A pair of strips 18 is mounted on the pintle 15 adjacent the inner faces of the side arms 14 of the handle 12. These strips 18 are provided at their ends with lugs 19 which are pasted in position over the free ends of the side arms 14 in a manner to retain the strips 18 against pivoting with relation to the handle 12.

Fastening means is mounted on the strips 18 for releasable gripping an edge portion of the blade 10 to hold the blade against pivoting relative to the handle 12. This means comprises a pin 20 mounted on one of the strips 18 adjacent one edge portion of the blade 10. A block of rubber 21 is mounted on the other strip 18 on the opposite side of the fan blade 10 in alignment with the pin 20. When the pin 20 is moved towards the fan blade 10 it will force the fan blade against the rubber material 21 and the pointed end thereof will grip the adjacent end of the fan blade to assist the frictional engagement of the fan blade against the rubber material 21 in holding it against pivoting.

Means is also provided for holding these strips 18 in a position in which the pin 20 and rubber material 21 will grip the fan blade 10. This means comprises a rotative bushing 22 having a threaded portion 23. This bushing 22 is rotatively mounted upon one of the strips 18 and is cooperative with a complementary bushing 24 fixedly mounted on the other of the strips 18. The bushing 24 is formed with a threaded opening to receive the threaded projecting portion 23 of the rotative bushing 22.

Engagement of the rotative bushing 22 with the fixed bushing 24 will cause the strips 18 to be urged together and maintained in this relationship so that the pin 21 and rubber material 22 will grip the fan blade 10.

The rotative bushing 22 has a head aligned with an opening 25 formed in the adjacent side arm 14 of the handle 12 permitting a screw driver or other turning tool to be engaged with this head for turning the rotative bushing 22.

A suitable snap arrangement may also be used for holding the strips 18 in position. The free ends of the strips 18 are provided with inwardly directed bulged portions 26, as shown in Fig. 7, which are adapted to grip the fan blade 10 when it is pivoted to the inoperative position, illustrated by the dot and dash lines 10' in Fig. 6 for frictionally maintaining the fan blade 10 in this inoperative position. In other respects this form of the invention is similar to that previously shown and like reference numerals identify like parts in each of the several views.

The handle 12 is shown with a blocked out portion 12^a to permit an illustration or photograph 12^b, secured to the inner face of the handle, to be viewed therethrough. A match package 12^c is secured to the opposite side of the handle 12 to provide additional utility for the fan.

This folding pocket fan may also be sold without any advertising matter thereon, with any pictorial illustration, calendar, or other ornamentation. It may be used as a fan during warm days or as a tray under glasses, bottles, etc.

While I have illustrated and described the preferred embodiments of my invention, it is to be understood that I do not limit myself to

the precise constructions herein disclosed and the right is reserved to all changes and modifications coming within the scope of the invention as defined in the appended claims.

Having thus described my invention, what I claim as new, and desire to secure by United States Letters Patent is:

1. A folding pocket fan, comprising a flat fan blade, a flat strip of sheet material bent at its center forming side arms which are slightly longer than the height of said blade, and having the ends of its side arms engaging over an edge portion of said blade, and a pintle engaging through the ends of said arms and said edge portion of said blade, washers mounted on said pintle to the sides of said blade, a pair of strips mounted on said pintle adjacent the inner faces of said side arms and having top lugs attached upon said side arms, and fastening means mounted on said pair of strips for releasably gripping said edge portion of said blade, said means comprising a pin on one of said strips on one side of said fan blade and a piece of rubber material mounted on the other of said strips on the other side of said fan blade, and means for urging said strips together to cause said pin to engage said fan blade and press it against said rubber material.

2. A folding pocket fan, comprising a flat fan blade, a flat strip of sheet material bent at its center forming side arms which are slightly longer than the height of said blade, and having the ends of its side arms engaging over an edge portion of said blade, and a pintle engaging through the ends of said arms and said edge portion of said blade, washers mounted on said pintle to the sides of said blade, a pair of strips mounted on said pintle adjacent the inner faces of said side arms and having top lugs attached upon said side arms, and fastening means mounted on said pair of strips for releasably gripping said edge portion of said blade, said means comprising a pin on one of said strips on one side of said fan blade and a piece of rubber material mounted on the other of said strips on the other side of said fan blade, and means for urging said strips together to cause said pin to engage said fan blade and press it against said rubber material.

3. A folding pocket fan, comprising a flat fan blade, a flat strip of sheet material bent at its center forming side arms which are slightly longer than the height of said blade, and having the ends of its side arms engaging over an edge portion of said blade, and a pintle engaging through the ends of said arms and said edge portion of said blade, washers mounted on said pintle to the sides of said blade, a pair of strips mounted on said pintle adjacent the inner faces of said side arms and having top lugs attached upon said side arms, and fastening means mounted on said pair of strips for releasably gripping said edge portion of said blade, said means comprising a pin on one of said strips on one side of said fan blade and a piece of rubber material mounted on the other of said strips on the other side of said fan blade, and means for urging said strips together to cause said pin to engage said fan blade and press it against said rubber material, said latter means comprising a rotative bushing on one of said strips and formed with a threaded projection and a complementary bushing fixedly mounted on the other of said strips and formed with a threaded recess adapted to be engaged by said threaded projection.

4. A folding fan, comprising a flat fan blade, a flat strip of sheet material bent at its center forming side arms which are slightly longer than the height of said blade, and having the ends of its side arms engaging over an edge portion of said blade, and a pintle engaging through the ends of said arms and said edge portion of said blade, washers mounted on said pintle to the

sides of said blade, a pair of strips mounted on said pintle adjacent the inner faces of said side arms and having top lugs attached upon said side arms, and fastening means mounted on said pair of strips for releasably gripping said edge portion of said blade, said means comprising a pin on one of said strips on one side of said fan blade and a piece of rubber material mounted on the other of said strips on the other side of said fan blade, and means for urging said strips together to cause said pin to engage said fan blade and press it against said rubber material, said fan blade being pivotal to an inoperative position between said strips and means on said strips for frictionally engaging said fan blade to maintain it in its inoperative position.

5. A folding pocket fan, comprising a flat fan blade, a flat strip of sheet material bent at its center forming side arms which are slightly longer than the height of said blade, and having the ends of its side arms engaging over the edge portion of said blade, and a pintle engaging through

10 the ends of said arms and said edge portion of said blade, washers mounted on said pintle to the sides of said blade, a pair of strips mounted on said pintle adjacent the inner faces of said side arms and having top lugs attached upon said side arms, and fastening means mounted on said pair of strips for releasably gripping said edge portion of said blade, said means comprising a pin on one of said strips on one side of said fan blade and a piece of rubber material mounted on the other of said strips on the other side of said fan blade, and means for urging said strips together to cause said pin to engage said fan blade and press it against said rubber material, said fan blade being pivotal to an inoperative position between said strips and means on said strips for frictionally engaging said fan blade to maintain it in its inoperative position, said latter means comprising inwardly extended bulges arranged to engage opposite faces of said fan blade when in an inoperative position.
